UNITED STATES PATENT OFFICE.

JAMES E. DE GRUSH AND JOHN WROATH, OF SANDY HILL, NEW YORK.

SIDE-BAR VEHICLE.

SPECIFICATION forming part of Letters Patent No. 227,499, dated May 11, 1880.

Application filed March 20, 1880. (Model.)

To all whom it may concern:

Be it known that we, JAMES E. DE GRUSH and JOHN WROATH, of Sandy Hill, in the county of Washington and State of New York, have invented certain new and useful Improvements in Side-Bar Vehicles; and we do hereby declare that the following is a full, clear, and exact description thereof, reference being had to the accompanying drawings, and to the letters of reference marked thereon, which form part of this specification.

The nature of our invention relates to the construction and arrangement of a buckboard-wagon, as will be hereinafter more fully set forth, and pointed out in the claim.

In order to enable others skilled in the art to which our invention appertains to make and use the same, we will now proceed to describe its construction and operation, referring to the annexed drawings, in which—

Figure 1 is a perspective view of our device, and Fig. 2 is a cross-section.

A represents the front axle, with head-block B, and C is the rear axle. The head-block B and rear axle, C, are connected by the two bars or boards D D, which form what is known as the "buckboard."

E is the seat-frame above the boards D, said frame being supported upon posts or blocks a a, extending upward from the side bars, F F. These side bars are connected by and supported upon sills G G, which pass un-

der and are secured to the boards D D. A rod or bar, H, connects the front sill with the head-block B.

Under the boards D D is placed a cross-bar, I, and above or on top of the frame E is another cross-bar, I', which two bars are connected and held in place by a central screw, J.

By this device the spring of the buckboard can be regulated very quickly, according to the weight of the load, or according as the road is rough or smooth, without getting out of the wagon.

This device may be used with a wagon-body on the buckboard, and it will spring as easy as if there were only a seat fastened to it.

The device is simple, cheap, and durable, and not liable to break or get out of order.

Having thus fully described our invention, what we claim as new, and desire to secure by Letters Patent, is—

In combination with the buckboard D D and frame E, the cross-bars I I' and the connecting and regulating screw J, substantially as and for the purposes herein set forth.

In testimony that we claim the foregoing as our own we affix our signatures in presence of two witnesses.

JAMES E. DE GRUSH.
JOHN WROATH.
